UNITED STATES PATENT OFFICE.

JOSEPH A. MAYNARD, OF RAVENA, NEW YORK.

FOLDING CAR-STEP.

1,149,934.

Specification of Letters Patent. Patented Aug. 10, 1915.

Application filed October 9, 1913. Serial No. 794,232.

To all whom it may concern:

Be it known that I, JOSEPH A. MAYNARD, a citizen of the United States, residing at RAVENA, in the county of Albany and State 5 of New York, have invented certain new and useful Improvements in Folding Car-Steps, of which the following is a specification.

This invention relates to improvements in folding car steps and one of the objects of 10 the invention is to operate a folding step by fluid pressure means wherein one movement of the step is effected under fluid pressure and whereby another movement of the step may be effected by gravity.

15 A further object of the invention is to provide a folding step, in subjacent relation to the lowermost fixed step, the folding step being arranged to pass in overhanging relation with the lowermost fixed step and lie 20 wholly within the outer edge thereof so as to avoid the presence of any projecting parts when the step is folded.

Further objects and features of the invention will be more fully described in connection 25 with the accompanying drawing and will be more particularly pointed out and ascertained in and by the appended claims.

In the drawing:—Figure 1 illustrates the 30 device of my invention applied to the steps of a passenger coach, looking endwise of the step and illustrating a portion of the operating means in section. Fig. 2 is a perspective view of the lowermost fixed and the subjacent folding step with a portion of the operating 35 means omitted. Fig. 3 is an end view looking in a direction opposite from the direction in which the structure of Fig. 1 is viewed.

Like characters of reference designate 40 similar parts throughout the different figures of the drawing.

As shown, 1, 2 and 3 designate the fixed 45 steps of a passenger coach arranged in overhanging relation with respect to each other and mounted upon a support 4. The lowermost fixed step 3 is arranged so as not to project beyond or outside of the plane of the coach, which is indicated at 5.

A folding step is indicated at 6 and when 50 in an operative position the same is disposed in subjacent relation with respect to the lowermost fixed step 3 and may project outside of as well as below the coach 5 so as to facilitate mounting the steps by the passengers. In Fig. 1 I have shown in dotted lines the position of the step 6 when

in a folded or in an inoperated position wherein it will be seen that the folded step not only lies wholly within the outside plane of the coach as indicated at 5, but it also 60 overhangs the lowermost fixed step and lies abreast of the outer edge of the next lowermost step 2, so as to effectively obstruct any attempt to enter the coach by means of the step when the folded step is in an inoperative 65 position.

Referring to the manner in which the step 6 is mounted, 7 designates a step-supporting arm which is arranged and disposed in a plane outside of the end edge of the fixed 70 step 3 and is mounted at 8. The pivot 8 may be secured to a bracket 9 which is shown anchored to the bottom of the lowermost fixed step 3. The step-supporting arm 7 extends outside of the plane of the end 75 edge of the step 6 and inwardly under the same to form a foot 10, adapted to be secured by means such as a screw 11 to the bottom of the step 6. The arm 7 is provided with an abutment shoulder 12 adapted to cushion against a yielding abutment 13 which may be mounted upon a support 14, pendant from the step 3. This abutment serves to limit downward movement of the arm 7 so that the same will be arrested 80 at such a point as will dispose the folding step 6 in a substantially horizontal plane when in an operative position, as shown in Fig. 3.

On the other end of the step 3, I mount 90 a bracket 15 having a pivot or trunnion 16 on which a step-supporting arm 17 is mounted to swing. The arm 17 is also mounted to swing in a plane outside of the end of the step 3, as indicated in Fig. 2. Said arm 17 95 is provided with a foot 18 which extends beneath the step 6 and is adapted to be fastened to the same by means such as screws 19. The arm 17 may be termed the operating step arm by reason of its connection 100 with operating means whereby the step is moved into and out of folded positions, and to distinguish the arm 17 from the arm 7, which latter functions simply as the supporting arm.

The operating arm 17 is provided with an extension 20 to which a link 21 is pivotally mounted at one of its ends. The other end of the link 21 is pivotally connected at 22 to a piston rod 23 of a piston 24. The 110 piston 24 is reciprocable in a cylinder 25, adapted to be mounted in any suitable man-

- ner to the step structure, as indicated at 26. The piston 24 is actuated by fluid pressure entering through a pipe 27 to move the step into a folded position and by fluid pressure 5 entering through a pipe 28 to move the step from a folded position into an operative position. Fluid pressure may be supplied through a pipe 29 through a suitable valve 30, controllable by a lever indicated at 31.
- 10 The device is arranged so that when the piston 24 is in the full line position to dispose the step 6 in an operative position, said piston 24 will then be at the upper end of the cylinder and I provide a bumper 32 to 15 cushion abutment of the piston 24 in this position. The bumper 32 is provided with a port 33 for passage of pressure fluid therethrough. This arrangement and construction not only serves to neutralize the shock 20 and jar incident to sudden arrest of movement of the parts when the step is being unfolded; but the bumper 32 also functions to yieldingly support the step 6 and the arrangement further provides for imparting 25 strain to the piston rod and the link 21 in the direction of their length and in a manner to cause the same to act as strut-supporting parts.

It will be seen by reference to Fig. 1 that 30 the arms 7 and 17 are pivoted and shaped in a manner to cause the folding step to normally seek an unfolded or operative position by gravity so that when it is in an unfolded position, the normal weight of the step 35 itself will take up any looseness in the connection and resist movement of the step out of an operative position so as to provide a firmly positioned step upon which to tread. Therefore while I have shown a 40 fluid pressure connection 28 to move the piston 24 from the dotted line to the full line position, it will be understood that in a great measure the step itself will move in such position by gravity. I also prefer to 45 cushion abutment of the piston 24 when arrested in the dotted line position and I therefore provide a bumper 34 having a laterally disposed port 35 for passage of pressure fluid.

50 It will be seen from the foregoing disclosure, that I have provided means which spans the ends of the fixed step and which are disposed inside of the outer edge of the fixed step for holding the movable step in 55 subjacent outward relation with respect to the fixed step for raising the movable step into an inoperative position, which is an overhanging position with respect to the outer edge of the fixed step.

60 It will be seen that the fixed step lies inwardly with respect to the side of the car and that when the movable step is folded it not only lies inwardly of the side of the car but all operative parts lie inwardly from 65 the side of the car.

While I have herein shown and described one specific form of my invention, I do not wish to be limited thereto except for such limitations as the claims may import.

I claim:

- 70 1. In a folding car step structure, a fixed step, a folding step, and fluid pressure means for operating the folding step including a cylinder having a yielding bumper head, and a piston movable under pressure to fold said step into an inoperative position and movable by weight of the step against said bumper to support the step in an operated position, substantially as described.
- 75 2. In a car step structure, a fixed step, a movable step, pivoted arms disposed outside of the ends of the movable and fixed steps for supporting the movable step in an operative position subjacent to and projecting 80 from the outside edge of the fixed step or in overhanging relation with and inside of the outside edge of the fixed step, an abutment for engagement with one of said arms to hold the step in an operative position, and means connected with another of said arms for moving said movable step, substantially as described.
- 85 3. In a car step structure, a fixed step, a movable step, arms pivotally mounting the 90 movable step for movement above or below the fixed step, means connected with one of said arms for moving the movable step and including a piston and cylinder, and a bumper in the cylinder for limiting movement of the piston in one direction to support the movable step in an operated position, substantially as described.
- 95 100 4. In a car step structure, a fixed step, a movably mounted step, fluid pressure means 105 for shifting said movable step into an inoperative position with respect to the fixed step, and a bumper device incorporated in said fluid pressure means for arresting operation thereof upon movement of said movable step into an operative position to support the same in such position, substantially as described.
- 110 5. In a car step structure, a fixed step, brackets at each end of said step, a supporting arm pivoted to one of said brackets, an operating arm pivoted to the other of said brackets, foot portions formed on each of said arms, an extension formed on said operating arm, a movable step mounted by 115 120 and between said arms, fluid pressure means for actuating said operating arm to fold said movable step over said fixed step or to extend the former into operative position, and link means connecting said extension with said fluid pressure means, substantially as described.
- 125 6. In a car step structure, a fixed step, brackets at each end of said step, a supporting arm pivoted in one of said brackets 130

to swing by the edge of said step, an operating arm similarly pivoted in the other of said brackets and formed with an extension, a piston operable by fluid pressure in either direction, a link connecting said piston with said extension, a movable step supported by and between said arms, and a bumper device coacting with said piston to arrest operation thereof upon movement of said movable step into operative position, substantially as described.

7. In a car step structure, a fixed step, brackets at each end of said step, a supporting arm pivoted in one of said brackets to swing by the edge of said step, an operating arm similarly pivoted in the other of said brackets and formed with an extension, a piston operable by fluid pressure in either direction, a link connecting said piston with said extension, a movable step supported by and between said arms, a bumper device coacting with said piston to arrest operation thereof upon movement of said movable step into operative position, and a yielding

abutment adapted to coact with said supporting arm to similarly function with said bumper, substantially as described. 25

8. In a car step structure, a fixed step, a pair of arms pivoted to swing by the edges of said step, an abutment formed on one of said arms, an extension formed on the other of said arms, foot portions formed on both of said arms, a movable step supported by said foot portions and between said arms, cushioning means to coact with said abutment when said movable step is in an operative position, fluid pressure means for moving said step by acting upon said extension, and a bumper device incorporated into said means to arrest operation of said step in 30 such operative position, substantially as described. 35

In testimony whereof I affix my signature in presence of two witnesses.

JOSEPH A. MAYNARD.
